(57) **CLAIM**

The ornamental design for a surgical scrub v-neck shirt, as shown and described.

DESCRIPTION

FIG. 1 is a front view of a surgical scrub v-neck shirt showing our new design;

FIG. 2 is a rear view of the design shown in FIG. 1; and, FIG. 3 is a front view of a surgical scrub v-neck shirt showing our new design, the rear viewing being identical to the view shown in FIG. 2.

The elements shown in broken lines are for illustrative purposes only and form no part of the claimed design.
